UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET COLLECTING, ASSOCIATING, AND FOLDING MACHINE.

1,305,989.

Specification of Letters Patent. Patented June 10, 1919.

Application filed February 28, 1917. Serial No. 151,546.

To all whom it may concern:

Be it known that I, HOWARD M. BARBER, a citizen of the United States, and resident of Stonington, in the county of New London 5 and State of Connecticut, have invented a new and useful Improvement in Sheet Collecting, Associating, and Folding Machines, of which the following is a specification.

The object of this invention is to provide 10 novel means for associating extra sheets fed from different sources of sheet supply, such, for instance, as cover and insert sheets, with a collected and folded group of sheets fed from another source of supply, means pref- 15 erably being employed for stitching the so associated sheets together and for folding the same.

A practical embodiment of my invention is represented in the accompanying drawings, in which,

Figure 1 is a detail longitudinal vertical central section through so much of a sheet collecting, associating and folding machine as includes my invention.

Fig. 2 is a similar section taken just inside the near side frame,

Fig. 3 is a similar section taken just inside the far side frame, and

Fig. 4 is a similar section taken just out- 30 side the far side frame showing the geared connection between the several parts.

1 designates a source of extra sheet supply, such, for instance, as an insert sheet supply. 2 designates a different source of extra sheet supply, such, for instance, as a cover sheet supply.

These sources 1 and 2 are herein shown as feed tables, the table 1 being provided with a movable sheet stop 3 and the table 2 with 40 a movable sheet stop 4.

Rotary cutters 5 and 6, mounted on suitable shafts 7, 8, are arranged to cut a single web or a plurality of superimposed webs, which pass through the rolls 9, 10, into 45 sheets, which sheets are passed downwardly between the guides 11, 12, and between the rotary coacting carriers 13, 14, mounted on shafts 15, 16, respectively. These carriers are arranged to collect the sheets in groups 50 and impart a transverse fold to the same. In the present instance, the rotary carrier 14 is provided with a set of grippers 17 and

a folding blade 18, which blade is arranged to coact with the folding jaws 19 on the rotary carrier 13, every two revolutions of 55 the rotary carrier 14.

A rotary associating carrier 21 mounted on the shaft 22 is herein shown as provided with an odd number of sets of grippers 23, 60 three for instance.

A rotary transfer carrier 24 mounted on a shaft 25 is arranged to feed the extra sheets successively from the sources of sheet supply 1, 2, into position to be associated on the associating carrier 21, with the folded 65 group of sheets from the rotary carrier 13. This rotary transfer carrier 24 is shown as having an even number of grippers, two for instance, the grippers 26 being arranged to take the sheets from the source of sheet 70 supply 1, and the grippers 26* being arranged to take the sheets from the source of sheet supply 2.

A stitcher table 27 is arranged to receive 75 the associated sheets where they are stitched transversely of their travel by the coacting parts 28, 29, of two or more stitchers. A movable stop 30 at the outer end of the stitcher table 27 is arranged in position to engage the advance edges of the associated 80 sheets and hold them momentarily in position for the stitching operation.

Coacting rotary carriers 31, 32, mounted on their respective shafts 33, 34, are provided; the carrier 31 having a set of grippers 85 35 arranged to take the stitched, associated sheets from the stitcher table 27. This carrier 31 is also provided with a folding blade 36 arranged to coact with the folding jaws 37 on the rotary carrier 32 for 90 imparting a transverse fold to the associated sheets along their transversely stitched line.

Endless carriers 38, 39, serve to carry the 95 associated sheets onto and off from a stitcher table 27 and endless carriers 40, 41, are arranged to carry the product from the rotary carrier 32 to a suitable delivery 42, 43.

The train of gears designated by 44 to 68 inclusive, is operative to drive the parts at the proper relative speeds. In the present 100 instance, the rotary carriers 13 and 14 are run at the same surface speed, the carrier 21 at a slightly greater surface speed and the carrier 24 at the same surface speed as

the carrier 21. The carriers 31 and 32 rotate one revolution to two revolutions of the rotary carrier 14.

5 A switch 69 is located at the entrance end of the stitcher table 27, which switch is operated from a cam 70 on the shaft 33 of the rotary carrier 31 through the connection 71.

10 A movable cam 72 for opening the grippers 23 at the proper intervals to receive the sheet fed from the extra source of sheet supply 1, is controlled by a cam 73 on the shaft 15 of the rotary carrier 13 through the connection 74.

15 A movable cam 75 for releasing the grippers 23 at the proper intervals to deliver the associated sheets, is controlled by a cam 76 on the shaft 15 of the rotary carrier 13 through the connection 77.

20 The coacting folding mechanism on the carriers 13 and 14 is of the well known floating blade and jaw type, in which the cam 78 controls the blade 18 and the cams 79, 80, 81, control the jaws 19.

25 A movable cam 82 controls the grippers 17 of the rotary carrier 14, and a fixed cam 83 controls the grippers 23 of the rotary carrier 21 at the point where they receive the folded groups of sheets from the rotary carrier 13.

30 The coacting folding mechanism of the rotary carriers 31, 32, is of the well known floating blade and jaw type, the operation of the blade 36 being controlled by the cam 84, and the operation of the jaws 37 being controlled by the cams 85, 86, 87.

35 The grippers 35 on the rotary carrier 31 are tumbler operated, the tumbler 88 being controlled by the pins 89, 90. The grippers 40 are opened to release the associated sheets at the time of folding, by the stationary cam 91. The grippers 26 on the rotary carrier 24 are tumbler operated, their tumbler 92 being operated by the pins 93, 94. The grippers 45 26* on the rotary carrier 24 are also tumbler operated, their tumbler 95 being controlled by the pins 96, 97. The movement of the sheet stop 3 is controlled by the cam 98 arranged to engage the sheet stop roller 40, and the movement of the sheet stop 4 is controlled by the cam 101 arranged to engage the sheet stop roller 103. The movement of the sheet stop 30 is controlled by the cam 98 arranged to engage the sheet stop roller 45, and the movement of the sheet stop 4 is controlled by the cam 101 arranged to engage the sheet stop roller 103. The movement of the sheet stop 30 is controlled by the cam 104 which is arranged to engage the sheet stop roller 50, and the sheet stop roller 105. The positively driven rollers 106, 107, bear against the surface of the rotary carrier 21, to hold the sheets in register thereon when the grippers are open, and a positively driven roller 108 55 engages the surface of the rotary carrier 24 to hold the sheets in register thereon when their grippers are open.

60 A fixed cam 109 opens the grippers 26 to permit the sheets fed from the extra source 65 of sheet supply 1, to be transferred to the

grippers 23 of the associating carrier 21. A fixed cam 110 opens the grippers 26* to release the sheets fed from the extra source of sheet supply 2, for association with the folded group of sheets and the extra sheet 70 fed from the source 1.

Mechanism is herein shown as arranged for association with a transversely once-folded group of sheets of an insert sheet fed from the source of supply 1, and a cover 75 sheet fed from the source of supply 2, with the insert on one side of the folded group of sheets and the cover on the other side thereof.

The rolls 9, 10, are arranged to feed one 80 or more webs to the rotary cutters 5, 6, where sheets are severed from the web or webs and fed through the guides 11, 12, to the collecting and folding carriers 13, 14. These carriers are, in the present instance, 85 arranged to collect two sheets or two groups of superimposed sheets and fold the same transversely of their travel onto the rotary carrier 13.

In the meantime, the rotary carrier 24 has 90 taken an insert sheet from the source of supply 1 and fed it to one of the grippers 23 on the associating carrier 21. As this gripper 23, with its insert reaches a point between the carriers 21 and 13, a folded 95 group of sheets is transferred from the carrier 13 to the carrier 21 on top of the insert sheet. As the associated insert and folded group of sheets reach a point between the carriers 24 and 21, a cover sheet, 100 which has been taken from the source of sheet supply 2 by the grippers 26* is placed on top of the folded group of sheets, and the so associated cover, insert and interposed folded group of sheets are then fed forwardly onto the stitcher table 27, the switch 69 being thrown into position to insure the passage of the insert sheet with the others onto the said table.

When these associated sheets reach the 110 stop 30, the sheets are stitched transversely of their travel. The stop 30 is then raised and the advance edges of the sheets are grasped by the set of grippers 35 on the rotary carrier 31. The associated sheets are 115 then folded off along their stitched line, transverse of their travel, onto the rotary carrier 32 and are delivered therefrom to the delivery mechanism 42, 43.

It is obvious that the rotary carriers 13, 120 14, can handle single sheets or a plurality of superimposed sheets fed from the rotary cutters 5, 6, and it is also obvious that the rotary carrier 24 can feed one sheet or a plurality of superimposed sheets from each 125 of the different sources of sheet supply 1 and 2, without departing from the spirit and scope of my invention.

It is evident that changes may be resorted to in the form, construction and arrange- 130

ment of the several parts without departing from the spirit and scope of my invention; hence I do not wish to limit myself strictly to the structure herein shown and described, 5 but

What I claim is:

1. Means for collecting and folding a group of sheets, a rotary carrier for associating extra sheets fed from different sources 10 with said folded group of sheets, and a common means for feeding the extra sheets successively to the associating means.

2. Means for collecting and folding a group of sheets, a rotary carrier for associating extra sheets fed from different sources 15 with said folded group of sheets, a common means for feeding the extra sheets successively to the associating means, and means for stitching the so associated sheets together and delivering the same.

3. Means for collecting and folding a group of sheets, means for associating extra sheets fed from different sources with said folded group of sheets, a common means for 20 feeding the extra sheets successively to the associating means, and means for folding the so associated sheets together and delivering the same.

4. Means for collecting and folding a group of sheets, means for associating extra sheets fed from different sources with said folded group of sheets, a common means for feeding the extra sheets successively to the associating means, and means for stitching and folding the so associated sheets together and delivering the same.

5. Rotary carriers arranged to collect and fold a group of sheets, a rotary carrier arranged to associate extra sheets fed from 40 different sources with the folded group of sheets, and means for stitching the so associated sheets together and delivering the same.

6. Rotary carriers arranged to collect and fold a group of sheets, a rotary carrier arranged to associate extra sheets fed from different sources with the folded group of sheets, and means for stitching and folding the so associated sheets together and delivering the same.

7. Rotary carriers arranged to collect and fold a group of sheets, a rotary carrier arranged to associate extra sheets fed from different sources with the folded group of sheets, and a rotary carrier arranged to feed the extra sheets to the sheet associating carrier.

8. Rotary carriers arranged to collect and fold a group of sheets, a rotary carrier arranged to associate extra sheets fed from different sources with the folded group of sheets, a rotary carrier arranged to feed the extra sheets to the sheet associating carrier, and means for stitching the so associated sheets together and delivering the same.

9. Rotary carriers arranged to collect and fold a group of sheets, a rotary carrier arranged to associate extra sheets fed from different sources with the folded group of sheets, a rotary carrier arranged to feed the extra sheets to the sheet associating carrier, and means for folding the so associated sheets together and delivering the same.

10. Rotary carriers arranged to collect and fold a group of sheets, a rotary carrier arranged to associate extra sheets fed from different sources with the folded group of sheets, a rotary carrier arranged to feed the extra sheets to the sheet associating carrier, and means for stitching and folding the so associated sheets together and delivering the same.

11. Rotary carriers arranged to collect and fold a group of sheets, a rotary carrier arranged to associate extra sheets fed from different sources with the folded group of sheets, and a rotary carrier arranged to feed the extra sheets successively to the sheet associating carrier.

12. Rotary carriers arranged to collect and fold a group of sheets, a rotary carrier arranged to associate extra sheets fed from different sources with the folded group of sheets, a rotary carrier arranged to feed the extra sheets successively to the sheet associating carrier, and means for stitching the so associated sheets together and delivering the same.

13. Rotary carriers arranged to collect and fold a group of sheets, a rotary carrier arranged to associate extra sheets fed from different sources with the folded group of sheets, a rotary carrier arranged to feed the extra sheets successively to the sheet associating carrier, and means for folding the so associated sheets together and delivering the same.

14. Rotary carriers arranged to collect and fold a group of sheets, a rotary carrier arranged to associate extra sheets fed from different sources with the folded group of sheets, a rotary carrier arranged to feed the extra sheets successively to the sheet associating carrier, and means for stitching and folding the so associated sheets together and delivering the same.

15. Rotary carriers arranged to collect and fold a group of sheets, a rotary carrier arranged to associate extra sheets fed from different sources with the group of sheets, and a rotary carrier arranged to feed the extra sheets to the sheet associating carrier, the parts being so timed that the sheet associating carrier will first take an extra sheet, then the folded group of sheets and finally associate therewith another extra sheet.

16. Rotary carriers arranged to collect and fold a group of sheets, a rotary carrier arranged to associate extra sheets fed from different sources with the groups of sheets,

a rotary carrier arranged to feed the extra sheets to the sheet associating carrier, the parts being so timed that the sheet associating carrier will first take an extra sheet, then 5 the folded group of sheets and finally associate therewith another extra sheet, and means for stitching the so associated sheets together and delivering the same.

17. Rotary carriers arranged to collect 10 and fold a group of sheets, a rotary carrier arranged to associate extra sheets fed from different sources with the groups of sheets, a rotary carrier arranged to feed the extra sheets to the sheet associating carrier, the 15 parts being so timed that the sheet associating carrier will first take an extra sheet, then the folded group of sheets and finally associate therewith another extra sheet, and means for folding the so associated sheets together and 20 delivering the same.

18. Rotary carriers arranged to collect and fold a group of sheets, a rotary carrier arranged to associate extra sheets fed from different sources with the group of sheets, a 25 rotary carrier arranged to feed the extra sheets to the sheet associating carrier, the parts being so timed that the sheet associating carrier will first take an extra sheet, then the folded group of sheets and finally associate 30 therewith another extra sheet, and means for stitching and folding the so associated sheets together and delivering the same.

19. Means for collecting and folding a 35 group of sheets, a rotary carrier arranged to associate extra sheets fed from different sources with the folded group of sheets, and a rotary carrier arranged to take the extra sheets at different points on the carrier and 40 feed them to the associating carrier at different times.

20. Means for collecting and folding a group of sheets, a rotary carrier arranged to associate extra sheets fed from different 45 sources with the folded group of sheets, a rotary carrier arranged to take the extra sheets at different points on the carrier and feed them to the associating carrier at different times, and means for stitching the so 50 associated sheets together and delivering the same.

21. Means for collecting and folding a group of sheets, a rotary carrier arranged to associate extra sheets fed from different 55 sources with the folded group of sheets, a rotary carrier arranged to take the extra sheets at different points on the carrier and feed them to the associating carrier at different times, and means for folding the so 60 associated sheets together and delivering the same.

22. Means for collecting and folding a group of sheets, a rotary carrier arranged to associate extra sheets fed from different 65 sources with the folded group of sheets, a

rotary carrier arranged to take the extra sheets at different points on the carrier and feed them to the associating carrier at different times, and means for stitching and folding the so associated sheets together and 70 delivering the same.

23. Means for collecting and folding a group of sheets, a rotary carrier having an odd number of surfaces upon which extra sheets fed from different sources are associated with each folded group of sheets, and a rotary carrier having an even number of surfaces on which the extra sheets are taken in succession from the different sources and from which they are fed at different times 75 to the associating carrier to be associated thereon with each group of sheets.

24. Means for collecting and folding a group of sheets, a rotary carrier having an odd number of surfaces upon which extra 80 sheets fed from different sources are associated with each folded group of sheets, a rotary carrier having an even number of surfaces on which the extra sheets are taken in succession from the different sources and from which they are fed at different times to the associating carrier to be associated thereon with each group of sheets, and means for stitching the so associated sheets together 85 and delivering the same.

25. Means for collecting and folding a group of sheets, a rotary carrier having an odd number of surfaces upon which extra sheets fed from different sources are associated with each folded group of sheets, a 90 rotary carrier having an even number of surfaces on which the extra sheets are taken in succession from the different sources and from which they are fed at different times to the associating carrier to be associated thereon with each group of sheets, and means for stitching the so associated sheets together 95 and delivering the same.

26. Means for collecting and folding a group of sheets, a rotary carrier having an 100 odd number of surfaces upon which extra sheets fed from different sources are associated with each folded group of sheets, a rotary carrier having an even number of surfaces on which the extra sheets are taken in succession from the different sources and from which they are fed at different times to the associating carrier to be associated thereon with each group of sheets, and means for folding the so associated sheets together and 105 delivering the same.

27. A source of main sheet supply, different sources of extra sheet supply, a rotary sheet associating carrier, means for collecting and folding a group of main sheets and

for feeding the group to the associating carrier and a common means arranged to take the extra sheets successively from the different sources of extra sheet supply and transfer them successively to the associating 110 115 120 125 130

carrier to be combined with the folded group of sheets.

28. A source of main sheet supply, different sources of extra sheet supply, a rotary sheet associating carrier, means for collecting and folding a group of main sheets and for feeding the group to the associating carrier, a common means arranged to take the extra sheets successively from the different sources of extra sheet supply and transfer them successively to the associating carrier to be combined with the folded group of sheets, and means for stitching the so associated sheets together and delivering the same.

29. A source of main sheet supply, different sources of extra sheet supply, a rotary sheet associating carrier, means for collecting and folding a group of main sheets and for feeding the group to the associating carrier, a common means arranged to take the extra sheets successively from the different sources of extra sheet supply and transfer them successively to the associating carrier to be combined with the folded group of sheets, and means for stitching the so associated sheets together and delivering the same.

30. A source of main sheet supply, different sources of extra sheet supply, a rotary sheet associating carrier, means for collecting and folding a group of main sheets and for feeding the group to the associating carrier, a common means arranged to take the extra sheets successively from the different sources of extra sheet supply and transfer them successively to the associating carrier to be combined with the folded group of sheets, and means for stitching and folding the so associated sheets together and delivering the same.

31. A source of main sheet supply, different sources of extra sheet supply, a rotary sheet associating carrier, means for collecting and folding a group of main sheets, and for feeding the group of sheets to the associating carrier, and a single rotary carrier arranged to take the extra sheets suc-

cessively from the different sources of extra sheet supply and transfer them successively to the associating carrier to be combined with the folded group of sheets.

32. A source of main sheet supply, different sources of extra sheet supply, a rotary sheet associating carrier, means for collecting and folding a group of main sheets, and for feeding the group of sheets to the associating carrier, a single rotary carrier arranged to take the extra sheets successively from the different sources of extra sheet supply and transfer them successively to the associating carrier to be combined with the folded group of sheets, and means for stitching the so associated sheets together and delivering the same.

33. A source of main sheet supply, different sources of extra sheet supply, a rotary sheet associating carrier, means for collecting and folding a group of main sheets, and for feeding the group of sheets to the associating carrier, a single rotary carrier arranged to take the extra sheets successively from the different sources of extra sheet supply and transfer them successively to the associating carrier to be combined with the folded group of sheets, and means for folding the so associated sheets together and delivering the same.

34. A source of main sheet supply, different sources of extra sheet supply, a rotary sheet associating carrier, means for collecting and folding a group of main sheets, and for feeding the group of sheets to the associating carrier, a single rotary carrier arranged to take the extra sheets successively from the different sources of extra sheet supply and transfer them successively to the associating carrier to be combined with the folded group of sheets, and means for stitching and folding the so associated sheets together and delivering the same.

In testimony, that I claim the foregoing as my invention, I have signed my name this 26th day of February, 1917.

HOWARD M. BARBER.
